(57) **CLAIM**

The ornamental design for dog clothes, as shown and described.

DESCRIPTION

FIG. 1 is a top perspective view of dog clothes, showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom elevational view thereof; and,

FIG. 9 is another perspective view thereof, shown in an environment of use as worn by a dog.

The broken lines outline of a dog represent environmental subject matter that form no part of the claimed design.

1 Claim, 9 Drawing Sheets(56)
